[57] CLAIM

The ornamental design for a stump feeder, as shown and described.

DESCRIPTION

FIG. 1 is a perspective view of a stump feeder showing my design;

FIG. 2 is a first side elevational view thereof;

FIG. 3 is a second side elevational as seen 90 degrees from that of FIG. 2;

FIG. 4 is a third side elevational view as seen from 90 degrees from that of FIG. 3;

FIG. 5 is a fourth side elevational view as seen from 90 degrees from that of FIG. 4;

FIG. 6 is a top plan view of the stump feeder showing my design; and,

FIG. 7 is a bottom plan view thereof.
